UNITED STATES PATENT OFFICE

2,256,828

BUMPING POST

Stanley W. Hayes, Richmond, Ind., assignor to
Hayes Track Appliance Company, Richmond,
Ind., a corporation of Indiana

Application October 28, 1939, Serial No. 301,717

10 Claims. (Cl. 104—254)

The present invention relates to improvements in bumping posts of the type in which a bumper head, located between the rails, is supported from the roadbed by compression and tension means, and more specifically by divergent compression members and by divergent tension members secured to the bumper head and to the roadbed, the term "roadbed" being used broadly to indicate ballast, ties, rails, or any of them.

The object of the invention is, in general, to provide an easily constructed and assembled, relatively light and low-cost bumping post of the requisite strength to sustain the severe shocks to which such structures are subjected, and applicable without change to rails of various heights.

More specifically, the object of the present invention is to simplify the construction of the bumping post, particularly the base structure or track fixtures, by means of which the divergent compression and tension members are secured to the roadbed.

In many respects the present invention is directed to improvements of bumping posts of the above-described type, such as those illustrated in applicant's Patents Nos. 1,910,990, 2,022,767, 2,053,556, and 2,073,694, granted on May 23, 1933, December 3, 1935, September 3, 1936 and March 16, 1937, respectively. The bumping posts disclosed in these patents are all of a type that might be termed "fabricated" bumping posts because they are in large measure made by welding together various structural elements. As indicated above, it is an object of the present invention to simplify the manufacture of bumping posts of this type by reducing the number of structural elements and by simplifying the necessary welding operations by changing the form of some of the elements.

Other objects and advantages of the present invention will become apparent from the ensuing description in the course of which reference is had to the accompanying drawings, in which:

Fig. 1 is a plan view of a bumping post constructed according to the present invention;

Fig. 2 is a vertical sectional view taken along the line 2—2 of Fig. 1;

Fig. 3 is a plan view upon an enlarged scale of the left tension track fixture plate;

Fig. 4 is a side elevational view of the plate shown in Fig. 3, illustrating the tension joint as a whole;

Fig. 5 is a medial vertical sectional view through the plate of Fig. 4;

Fig. 6 is a detailed perspective of the right-hand compression track fixture; and

Fig. 7 is a side elevational view of the fixture shown in Fig. 6.

Referring now to the figures and particularly to Figs. 1 and 2, it may be seen that the bumping post, indicated generally by reference character 10, comprises a bumper head 12 supported slightly off center upon a pair of rails 14 by a pair of compression members 16 diverging downwardly, outwardly and rearwardly from the bumper head and a pair of tension members 18 diverging downwardly, outwardly and forwardly from the bumper head. These members, which may generally be termed stress transmitting members, in themselves constitute no part of the invention and may be of the various types disclosed in the above-mentioned patents. More specifically, they may be, and are illustrated as being, of the type disclosed in Patent No. 2,073,694.

The present invention is directed particularly to the simplification of the arrangement for supporting the bumper head and the compression and tension members. The tension members are secured to the track 14 by a pair of track fixtures 20 of novel construction, and the compression members 16 are secured to the track by another pair of novel track fixtures 22. These track fixtures are hereinafter referred to as the tension and compression track fixtures, respectively.

Another feature of the present invention resides in the mode of attachment of tension and compression cross beams 24 and 26 of the track fixtures 20 and 22, respectively. These cross beams are provided for the purpose of preventing spreading of the track under impact.

Considering first the tension track fixture 20, reference is had more particularly to Figs. 3, 4 and 5. Only one of the track fixtures is shown, that for the left tension member, as the other fixture is symmetrical in all respects except for a slight change in the angle of a tension member receiving aperture to be described hereinafter, necessitated by the fact that the bumper head 12 is positioned slightly off center in accordance with the usual practice.

The track fixture 20 is readily and economically made from flat plate metal which is forged or otherwise formed with a substantially horizontal cross beam engaging portion 28, a substantially vertical rail web engaging portion 30, and an intermediate angular portion 32 angled to overlie the inclined upper surface of the rail base. The welding of the tension member 18 to the track

fixture is greatly facilitated by providing the fixture with a cup-shaped, upwardly extending upset portion or dome 34, which is apertured, as indicated at 36, to receive the tension member. The dome may be formed by any convenient means, as for instance a bulldozer. Thus, as illustrated best in Fig. 5, the dome 34 provides a considerable space on its underside into which a portion of the tension member 18 projects so that it may readily be welded, as indicated at 38, to the fixture. The construction is such that neither the tension member nor the welding extends beyond the plane of the under side of the intermediate angular portion 32 of the fixture.

The vertically disposed rail web engaging portion 30 is provided with a pair of spaced apart apertures 40, by means of which it may be bolted to the rail. The outer surface of the fixture may be cut away immediately underneath the apertures 40, as indicated at 42, to provide the necessary clearances for the securing means.

One of the advantages of the above-described track fixture resides in the fact that the tension cross beam 24 may be welded directly to the horizontal portion 28 of the fixture, thereby eliminating any blocks or the like as required in prior art structures. Another advantage of the track fixture, which results from the fact that the base plate is generally triangular in shape, is that a saving in material is effected and the welding of the horizontal portion to the cross beam facilitated.

The right compression track fixture 22 comprises a base plate 44 cut and formed like the tension track fixture, with a substantially horizontal portion 46, a vertically disposed portion 48, and an intermediate angular portion 50. The base plate has welded to it at right angles to the axis of the compression member a compression member abutment plate 52. Additional rigidity is given to the abutment plate and fixture as a whole by means of a generally triangular brace 54 welded to both the base and abutment plates.

The vertically disposed portion 48 is apertured, as indicated by reference character 56, and the outer surface is cut away, as indicated by reference character 58, for the reception of the bolts and securing nuts. The left compression fixture is symmetrical to the one described, except for the angular location of the abutment plate which must of necessity be different because of the fact that, as explained above in connection with the tension joint, the bumper head is supported slightly off center.

The described construction of the compression track fixture to which the compression member is welded to form a unitary whole is very simple and rugged. It, too, is so constructed that the compression cross beam 26 may very easily be welded to the horizontally disposed portions 46.

From the above-described detailed description, it may be seen that the present invention provides a considerably simplified bumping post and that the invention likewise comprehends features which may be applied to various types of bumping posts. For instance, the tension track fixture of the present invention may be utilized with various types of constructions, as may be compression track fixture. For instance, certain of the advantages of the invention may be realized in bumping posts wherein the cross beams are not utilized.

What I claim as new and desire to secure by United States Letters Patent is, as follows:

1. In a bumping post, a track fixture compris-

ing a generally triangular plate member apertured to receive a stress transmitting member, said plate member being provided with an upset portion surrounding the aperture to provide space 5 on the lower side of said plate member for welding the end of said stress transmitting member to said plate member.

2. In a bumping post, a track fixture adapted to be secured on the inner side of a rail, said fixture comprising a plate member formed with a substantially vertically disposed portion adapted to be secured to the web of the rail on the inner side thereof, a substantially horizontal portion adapted to be welded directly to a cross beam, and 10 an intermediate inclined portion adapted to overlie the inclined upper surface of the rail base.

3. In a bumping post, a tension track fixture adapted to be secured on the inner side of a rail, said fixture comprising a plate member formed 20 with a substantially vertically disposed portion adapted to be secured to the web of the rail on the inner side thereof and an inclined portion adapted to overlie the upper inclined surface of the base of a rail, said inclined portion of the 25 plate member being apertured for the reception of a tension member and provided with a dome surrounding said aperture to facilitate welding of the tension member thereto.

4. In a bumping post, a tension track fixture 30 secured on the inner side of a rail, said fixture comprising a plate member formed with a substantially vertically disposed portion adapted to be secured to the web of the rail on the inner side thereof and an inclined portion adapted to 35 overlie the upper surface of the base of the rail and a horizontally disposed portion extending beyond the base of the rail, said inclined portion of the plate member being apertured for the reception of a tension member and provided with 40 an upwardly extending dome surrounding said aperture to facilitate welding of the tension member thereto.

5. In a bumping post, a compression track joint comprising a base plate having a portion 45 adapted to be secured to the web of a rail, an inclined portion overlaying the inclined upper surface of the rail base and a horizontal portion extending beyond the base of the rail, a generally 50 rectangular abutment plate welded to all three portions of said base plate at right angles to the axis of a compression member, a compression member welded to said abutment plate, a generally triangular brace welded to said abutment and base plates on the side opposite the 55 compression member, and a cross beam welded to said horizontal portion of the base plate.

6. A bumping post, including in combination, 60 a bumper head, a pair of compression members diverging rearwardly, downwardly and outwardly to opposite points on a railway track, tension members diverging forwardly, downwardly and outwardly to opposite points on the track, tension and compression cross beams located below the track, and track fixture plates for said tension 65 and compression members provided with portions adapted to be secured to the track and with portions welded directly to said cross beams.

7. A bumping post, including in combination, 70 a bumper head, compression members diverging rearwardly, downwardly and outwardly from said bumper head to opposite points on a railway track, tension members diverging forwardly, downwardly and outwardly from said bumper head, tension and compression cross beams lo-

cated below the track, and track fixtures for said tension and compression members provided with vertical flanges adapted to be secured to the webs of the rails, inclined portions adapted to overlie the inclined upper surfaces of the bases of the rails, and horizontal portions projecting outwardly from the rails, said horizontal portions being welded directly to said cross beams.

8. A bumping post, including in combination, a bumper head, compression members diverging rearwardly, downwardly and outwardly from said bumper head, tension members diverging forwardly, downwardly and outwardly from said bumper head, track fixtures for said tension members comprising vertical portions adapted to be secured to the webs of the rails, inclined portions adapted to overlie the inclined surfaces of the bases of the rails, said inclined portions being apertured and upset to provide dome-like portions surrounding the apertures through which the tension members project and to provide spaces for welding the ends of the tension members to the fixtures, and compression track fixtures comprising similarly formed portions, compression member abutment plates welded to said fixtures and to said compression members at right angles to the axes of the latter, and braces welded to said abutment plates and fixtures on the sides opposite the compression members.

9. A bumping post, including in combination, a bumper head, compression members diverging rearwardly, downwardly and outwardly from said bumper head, tension members diverging forwardly, downwardly and outwardly from said

bumper head to opposite points on a railway track, tension and compression cross beams located below the track, track fixtures for said tension members comprising vertical portions adapted to be secured to the webs of the rails, inclined portions adapted to overlie the inclined surfaces of the bases of the rails, and horizontal portions secured directly to said tension cross beam, said inclined portions being apertured and upset to provide dome-like portions surrounding the apertures through which the tension members project and to provide spaces for welding the ends of the tension members to the respective fixtures, and compression track fixtures comprising similarly formed portions of which the vertical and horizontal portions are secured, respectively, to the webs of the rails and to said compression cross beam, compression member abutment plates welded to said fixtures and to said compression members at right angles to the axes of the latter, and braces welded to said abutment and base plates on the sides opposite the compression members.

10. In a bumping post, a track fixture comprising a plate member formed with a substantially vertically disposed portion adapted to be secured to the web of a rail, a substantially horizontal portion adapted to be welded directly to a cross beam, and an intermediate inclined portion adapted to overlie the inclined upper surface of the rail base, said plate as a whole being generally triangular in shape and converging toward the horizontal portion.

STANLEY W. HAYES.
